UNITED STATES PATENT OFFICE.

WILLIAM D. BARBER, OF CHICAGO, ILLINOIS.

COMBINED CRIB AND INTAKE.

1,078,658.

Specification of Letters Patent. Patented Nov. 18, 1913.

Application filed June 5, 1912. Serial No. 771,940.

To all whom it may concern:

Be it known that I, WILLIAM D. BARBER, a citizen of the United States, and resident of Chicago, in the county of Cook and State of Illinois, have invented a certain new and useful Improvement in a Combined Crib and Intake, of which the following is a description, reference being had to the accompanying drawings, which form a part of my specification.

My invention relates to a water intake and crib for use in connection with the water supply of a municipality, adapted to be built or set in the body of water, from which the supply is had, at a distance from the shore line whereby the water is supplied by gravity to the pumping station or stations on shore.

The invention has for its object the provision of a crib provided with radially arranged intakes or pipes intended to be submerged and extend to a considerable distance from the crib so as to increase the area of supply and thereby reduce the suction effect heretofore encountered at the intake ports of cribs as previously constructed. Another object being to provide a crib wherein the intake-shaft which leads to the shore or pumping stations will have direct communication with the well of the crib, thereby eliminating the usual intake which heretofore formed an extension of the shaft rising into the well where it has been fitted with suitable sluice gates, so that repair of the gates and screens would permit the foreign matter to drop into the well or intake-shaft. In the employment of my improved construction, however, the intake ports of the crib are so formed that the gates and screens are arranged to the outside of the well of the crib where any repair of the gates or cleaning of the screens will be to the outside of the well and within a gallery or shaft with which my improved crib is provided, thus insuring a purer water supply passing into the intake-shaft leading to the shore or pumping station.

A further object of my invention is the provision of a crib having intake-pipes or conduits so constructed that water will be prevented from directly passing into the intake ends of the pipes or orifices, but be compelled to pass in a round about manner, or rather from a direction leading or tending toward the bottom of the lake or other

body of water; the construction being such that no suction effect will be induced to cause surface water to flow into the intakes, but on the other hand all the water will be drawn from points near the bottom of the lake, thus eliminating the difficulties heretofore encountered through sudden changes in velocity and direction of flow, cross currents, etc.; the construction being such that the intake ends or ports will not become obstructed by ice, etc., and, therefore, overcoming the great difficulties heretofore caused by anchor ice.

A further object of my invention is to provide a crib construction wherein it is made possible to thaw any ice that might form or become lodged at the intake ends of the intake pipes or conduits; the invention possessing other advantages inherent in the construction, which will be readily apparent from the following detailed description.

In the drawings:—Figure 1 is a sectional plan view taken on the irregular line 1—1 of Fig. 2, looking downwardly. Fig. 2 is a vertical sectional view taken on the irregular line 2—2 of Fig. 1, looking in the direction of the arrows. Fig. 3 is a diagrammatic view of my improved combination crib and intake. Fig. 4 is a diagrammatic view partly in elevation and partly in section. Fig. 5 is a detail view of the intake ends of one of the intake conduits or pipes, a portion thereof being shown in cross-section. Fig. 6 is a plan view of the detail shown in Fig. 5. Fig. 7 is a detail view, partly in section of one of the gates and screens located in the ports. Fig. 8 is a plan view of the same.

In the exemplification of my invention as illustrated in the drawings, the crib is composed of an outer steel or metallic shell 12 and an inner or concentric shell 13, maintained in proper relative position by the radially extending partitions 14, of which any suitable number may be employed; and the spaces between the different partitions 14 are provided with bottoms 15, more clearly shown in Fig. 2, preferably composed of sheet metal and properly secured to the shells 12 and 13, as well as to the adjacent partitions 14. The bottoms 15 are preferably secured a distance within the shells 12 and 13 so as to leave the ends of the shells 12 and 13 to extend somewhat below the bottoms 15, as clearly shown at 12^a and 13^a.

2

in Fig. 2. The bottoms 15 may be formed as just described, that is, a separate bottom for each of the compartments formed by adjacent partitions 14 and the concentric shells 12 and 13, or a single annular plate may be secured beneath the bottoms of the partitions 14 so as to form water-tight compartments; the partitions, of course, need not extend to the bottom edges 12^a and 13^a of shells 12 and 13 respectively. The shells 12 and 13 may, of course, be made of any suitable size, as for example, the outer shell may be 100 feet and the inner shell 50 feet in diameter so as to provide an annular space of considerable size between them, which annular space, as previously described, is divided into a series of water-tight compartments by the radially extending partitions 14, and bottom or bottoms 15. By securing the bottom or bottoms 15 within the shells 12 and 13 at a distance removed from the lower edges thereof, a cutting edge is provided which enables the shells to cut or press themselves into the clay bottom of the lake or body of water after the crib has been settled into place.

At a point preferably immediately above the bottom or bottoms 15, the shells 12 and 13 are provided with openings or ports, preferably in an aligned position intermediate of the partitions 14, as more clearly shown in Fig. 1. The ports or openings in the outer shell are surrounded by flanges 16, secured to the outer shell in any suitable manner, the flanges being intended to receive the flanged ends of suitable intake pipes 17, which are provided with orifices or intakes 18, preferably placed and sunken at a considerable distance from the crib itself.

In the preferred form of my invention, the intake ports or conduits 19 are bifurcated or provided with ramifications 19^a and 19^b, as more clearly shown in Fig. 1; and, therefore, the outer shell 12 is provided with two flanges 16 in each compartment intermediate of adjacently placed partitions 14; the bifurcations of the intake ports being preferably so arranged that the intake pipes or conduits connected thereto will be arranged radially and the intake area greatly spread, so that the water within this area will not be subjected to such action as would tend to quick or sudden changes. The inner shell 13 also has its ports surrounded by suitable flanges as shown at 20, to which suitable steel frames and fittings may be secured so as to receive sluice gates 21, which latter may be of any suitable construction and operable in a vertical direction.

The frames secured to the flanges 20 of the inner shell 13 are preferably also constructed so as to accommodate or receive suitable screens, arranged forward of the sluice gates, as more clearly shown at 22, see Figs.

1, 2, 7, and 8; the sluice gates and screens being located within the respective compartments formed intermediate of the inner shell 13 and outer shell 12 and partitions 14, and operable in shafts built within the compartments. It is apparent therefore that with my improved construction the sluice gates and screens are located outside of the well indicated at 23, formed within the inner shell 13, thereby insuring a purer water supply than with constructions at present in use. The screens 22, which like the sluice gates 21, are preferably arranged to move vertically in the respective shafts 25 by means of a well known construction of guide-ways; the screens and sluice gates being of any well known constructions. In the exemplification, I have chosen to illustrate a screen (which may be wire mesh or perforated sheet metal), the main or body portion whereof is somewhat in the nature of a basket with the one wall, preferably the one adjacent to the sluice gate, being extended vertically as very clearly shown in Figs. 2 and 7 so as to normally extend across the entire orifice or inlet; the vertically disposed side or portion of the screen preventing solids or foreign matter passing through the inlet when the sluice gate is open; while the horizontally disposed or basket portion will facilitate the solids or foreign matter lodging within the bottom of the respective shafts 25 being brought or drawn upward, as is clearly apparent, by means of a cable or other mechanism being secured to the main body portion thereof. It is understood, however, that the essential function of the screen is to prevent the passage of solids through the inlets when the sluice gate is open, so that whatever the construction of the screen may be, it should be provided with a vertically disposed portion completely covering the opening formed by the sluice gates.

In practice, the steel shells 12 and 13 together with the radially extending partitions 14 and the bottom or bottoms 15 are built before the steel crib is towed out to the point where it is to be located; the shells having been provided with the ports previously described, which have also been provided with the flanges heretofore referred to; and, if desired, the intake conduits 19 may also be built into place before the crib is towed out. The openings or ports in both the interior and outer shells are properly capped or closed so that a series of watertight compartments will be provided intermediate of the inner and outer shells which will maintain the construction afloat until the point where the crib is to be located has been reached.

It is evident from the construction just described that the opening of the respective ports by the removal of the cap or plug

will permit the different compartments to fill with water in an even and uniform manner, which will compel the shell construction of the crib to gently settle into place.

- 5 In order that the shell construction may become firmly embedded in the bottom of the lake or other body of water, the bottom 15 of each compartment is preferably pierced by a flanged pipe 24, see Fig. 2, whereby the 10 water located beneath the bottom of the compartments and intermediate of the depending edges of the shells 12 and 13 may be pumped or drawn from under each compartment and permit the depending edges 15 of the concentric shells to cut into the clay or bottom until the bottom 15 of the compartments rests upon the clay bottom of the body of water; the entire structure being thus firmly drawn or settled into its final 20 position. The shells 12 and 13, it will be understood, are of such width vertically that they will extend a sufficient distance above the surface of the water when in final settled position. After the shell construction 25 has thus become finally settled into place, which is, of course, at the point where the intake shaft, which leads to the shore or pumping station, terminates, the various 30 water-tight compartments formed by the inner and outer shells and the radially disposed partitions, are then pumped out, preferably one at a time, the compartments are then filled in with suitable material, as for example adjoining the inner and outer 35 shells a wall of concrete of sufficient thickness is built so as to provide a shaft 25 in each compartment, extending from the intake ports up to the upper edge of the shells or top of the crib, as very clearly indicated 40 in Fig. 2; concrete being preferably employed around the various ports and shafts and adjacent the shells, while the space intermediate of the concrete walls thus formed may be filled with broken stone, clay and 45 sand thoroughly puddled and tamped up to a point which is to constitute the floor of the crib, namely a proper distance above the water level. The sluice gates, screens, and operating mechanism for the gates and 50 screens are then built in each shaft.

The various compartments or pockets having been finished in the manner just described, the space within the inner shell 13 is then pumped out and a well 23 built therein preferably of concrete as shown in Fig. 2, preferably with sloping or converging walls, as shown in Fig. 2, terminating in an opening at the top, inclosed by a suitable superstructure, whereby access and 55 proper observations may constantly be had; the upper part of the well being lined with suitable light reflecting material, if desired, The lower part of the well, of course, is provided with the ports as shown at 26 in Fig. 60 2, in alignment with the intake ports or con-

duits 19; and the well terminates in or communicates at its bottom with the intake shaft 27, whereby the water is conveyed or permitted to flow from the well to the pumping station on shore.

After the well has been completed, the intake pipes or conduits 17, which are preferably laid in trenches excavated in the bottom of the lake, or other body of water, are then secured to the flanged couplings 16 70 secured about the ports of outer shell 12, as very clearly shown in Fig. 2. The intake pipes, of which I illustrate two to each port 19, may be made to extend different distances from the crib as indicated for example in the diagrammatic views 3 and 4.

The outer or inlet ends of the intake pipes 17 are presented upwardly as very clearly shown at 18 in Fig. 5; the intake ends being preferably provided with an anchor or support as indicated at 27, see Fig. 5, of a suitable construction whereby the inlet ends 18 75 are maintained in proper elevated position. The orifices of the intake ends 18 are provided with hoods, as indicated at 28, preferably of steel and cone shaped as indicated in Fig. 5, so that the water will not flow into the intake ends 18 from a point immediately above, but be compelled to flow into the intake pipes from a point below the plane of the orifices of the intake ends 18, as is readily apparent from the construction shown in Fig. 5.

In order that large particles of foreign substance cannot enter the intake pipes, I 100 prefer to support the hoods 28 by a grating as indicated at 29 which may be secured to the hood and the intake ends 18 in any suitable manner. The lower surface or insides of the hoods may be lined with zinc or brass, and the bars or grating 29 also be of polished brass, or other suitable metal, to which ice will not adhere. As the hoods 28 may be of considerable diameter, it is 105 evident that the area of inflow to each intake conduit or pipe will be distributed to a large area of the lake bottom.

In practice, it may be deemed advisable to surround the intake ends 18 of the intake conduits with concrete; and the intake pipes 115 at the point where they are secured to the outer shell of the crib may also be protected by a sufficient quantity of broken stone, as illustrated for example in Fig. 2, so as not to have the intake pipes subjected to the 120 effect of ice jams and other disturbances. With the hood construction at the intake ends of the intake pipes, any heavy material that may be dropped into the water from the surface would be deflected to one side 125 of the intake ends by the hood, while lighter materials would be less apt to pass into the intake ends because of the manner in which the water is compelled to flow into the intake pipes.

In the event of anchor ice forming in the hoods and intake ends, by reason of some disturbance which would cause water to be drawn from near the surface of the body of water, I provide a small pipe 30 along the sides of each intake pipe or conduit and terminating at a point near the apex within the hood; the pipe communicating with a suitable hot water tank located on the crib or in the superstructure thereon. Should such a condition arise, the intake gate of the particular intake conduit would then be closed and hot water allowed to flow through the pipe 30 by gravity, or otherwise, and be discharged within the hood at the intake end, whereby the anchor ice would soon be thawed and the intake pipe or conduit again restored to operative condition.

The upper ends of the shafts 25 may terminate in a suitable gallery or galleries as indicated for example at 31, see Fig. 2, which may completely surround the well 23, so that access to all of the shafts 25 may be readily had; the gallery or galleries which communicate with the shafts 25 being provided with any suitable mechanism whereby the respective gates and screens may be independently operated; the shafts 25 being provided with suitable guides or slide-ways for the gates and screens.

In addition to the gallery indicated at 31 in Fig. 2, one or more passages, as indicated at 32, may be provided, extending from the gallery to the upper part or restricted part of the well and above the water line thereof, so that access to the well may be had from the gallery 31, in which the gate and screen operating mechanism is preferably located. The well 23 is preferably provided with converging walls above the inlet ports therein, while the bottom of the well opens into the intake shaft as clearly shown in Fig. 2, the construction being such that cross and other currents of water will be diminished, and any material that may improperly enter the well will be permitted to rise to the top where it can be readily removed from the reduced or confined area at the well top.

The operating shafts 25 may be constructed of metal conduits of sufficient diameter and construction to permit of vertical movement of the sluice gates as well as the fish screens located adjacent thereto, built into place within the shells before the latter are towed to position; and the pipes 30 for conveying hot water or other ice thawing solution to the hooded inlet ends of the intake pipes may be arranged within each of the conduits or pipes 17, as illustrated in the drawings with the inner ends of these pipes 30 extending upward within the respective shaft 25 leading from the respective conduit.

I have shown and described what I believe to be the simplest and best form of my invention, which, however, may permit of

a number of modifications being made without, however, departing from the spirit of my invention, and I do not wish to be understood, therefore, as limiting myself to the exact construction shown and described, but 70

What I claim and wish to secure by Letters Patent is:-

1. A combined crib and intake, comprising a pair of spaced shells, means for maintaining them in proper relative position, the space intermediate of said shells being provided with a bottom so as to provide a water-tight inclosure between the shells, both shells being provided with ports in proximity to the lower edges thereof. 80

2. A combined crib and intake, comprising a pair of concentrically arranged spaced shells, means for maintaining said shells in proper relative position, the space intermediate of the shells being provided with a bottom at a distance removed from the lower edges of said shells so as to provide a water-tight inclosure between the shells, both shells being provided with radially arranged ports in proximity to and above the bottom, and 90 conduits or intake pipes communicating with said ports.

3. A combined crib and intake, comprising a pair of spaced shells, the space intermediate of said shells being provided with a bottom at a distance removed from the lower edges of the shells, and a series of ports arranged in aligned position in the inner and outer shell.

4. A combined crib and intake, comprising a pair of spaced shells, the space intermediate of said shells being provided with a bottom so as to form a water-tight inclosure between the shells, and a series of inlets extending from the outer shell to the space 100 within the inner shell.

5. A combined crib and intake, comprising a pair of spaced shells, the space intermediate of said shells being provided with a bottom at a distance removed from the lower 110 edges thereof so as to form a water-tight inclosure between the shells, a series of intake openings arranged in both of said shells whereby communication from without the outer shell may be established with the space 115 within the inner shell, and means for extracting water from beneath said bottom.

6. A combined crib and intake, comprising a pair of concentrically arranged shells, a series of vertically disposed partitions for 120 maintaining the shells in proper spaced relation, the space intermediate of said shells being provided with a bottom so as to provide a series of water-tight inclosures between the shells, both shells being provided 125 with radially arranged ports, and means whereby the ports may be controlled.

7. A combined crib and intake, comprising a pair of spaced shells, means for maintaining them in proper spaced relation, the 130

- space within the inner shell being provided with a well communicating with the intake shaft leading to the shore, both shells being provided with series of ports communicating with the well within the inner shell, and means arranged intermediate of the shells whereby the passage of water through said ports and into the well may be controlled. 5
8. A combined crib and intake adapted to be arranged at the orifice of the intake shaft leading to the shore and comprising a pair of spaced shells, means for maintaining said shells in proper spaced relation, the space intermediate of said shells being provided with a bottom arranged at a distance from the lower edges of said shells, inlet conduits arranged intermediate of the shells and in proximity to the bottom thereof whereby communication from without the outer shell may be had with the space within the inner shell, means whereby passage through the inlet conduits may be controlled, an operating shaft arranged intermediate of said shells and in vertical alignment with said means, and a well within the inner shell communicating with the intake shaft leading to the shore. 10
9. A combined crib and intake provided with a centrally disposed well communicating with the intake shaft leading to shore, a series of conduits communicating with said well, an operating shaft arranged about said well and intermediate of the ends of said conduits, and means located in said shaft whereby passage through said conduits may be controlled exterior of the well. 15
10. A combined crib and intake, comprising an inner wall and an outer wall, the space intermediate of both walls being inclosed by a bottom, a well arranged within the inner wall and communicating with the intake-shaft leading to shore, inlet ports extending through both walls and communicating with the well, port controlling means arranged intermediate of the inner and outer walls, and intake conduits communicating with the ports in the outer wall and terminating in upturned orifices at their outer ends. 20
11. A combined crib and intake, comprising an inner wall and an outer wall, the space intermediate of both walls being inclosed by a bottom, the space within the inner wall being provided with an upwardly converging well the bottom whereof communicates with the intake shaft leading to shore, a series of inlet ports extending through both walls and communicating with the well within the inner wall, a vertically disposed operating passage intermediate of the inner and outer walls, means mounted in said vertically disposed passage whereby the inlet ports are controlled, and a series of radially disposed intake conduits 25 communicating with the inlet ports, the outer ends of said conduits being provided with deflecting hoods. 25
12. In a combined crib and intake provided with a centrally disposed well communicating with the intake-shaft leading to shore, a series of conduits communicating with said well, deflecting means for the inlet ends of said series of conduits, said deflecting means being provided with sloping surfaces whereby the water is compelled to flow into said conduits from a plane below the plane of the orifices of said conduits. 30
13. In a combined crib and intake, the combination of an inner and an outer shell provided with inlet ports extending therethrough, means for maintaining a watertight inclosure intermediate of the shells, and a well arranged within the inner shell and with which the inlet ports communicate, said well having communication with the intake shaft leading to shore, with inlet conduits communicating with said inlet ports, the inlet ends of the conduits being provided with means whereby direct passage into the conduits will be prevented and a deflecting surface provided. 35
14. In combination with a crib and intake provided with a centrally disposed well communicating with the intake-shaft leading to shore, said well being provided with a series of inlets, of inlet conduits communicating with said well inlets, the orifices of said inlet conduits being provided with deflecting means whereby the water is compelled to flow into said conduits from a plane beneath the plane of said orifices, and means extending from the crib and intake to a point beneath the deflecting means of each orifice of said conduit whereby the formation of anchor ice about said orifices may be controlled. 40
15. A combined crib and intake, comprising a pair of spaced shells, the space intermediate of said shells being provided with a bottom so as to provide a water-tight inclosure between the shells, the space within the inner shell being provided with a well having a series of inlets and communicating at its bottom with the intake shaft leading to shore, a series of intake conduits arranged intermediate of the shells and communicating with the inlets of the well, the outer ends of said conduits being ramified so as to extend radially, a series of intake pipes connected with said ramifications and terminating alternately at different distances from the shells in upturned orifices, deflecting means arranged about said orifices, and means arranged intermediate of the inner and outer shells whereby passage through said conduits may be controlled. 45
16. A combined crib and intake, comprising a pair of concentrically arranged shells, means whereby the shells are maintained in proper spaced relation, and the space be- 50

between them divided into a series of compartments, a bottom provided intermediate of the shells and at a distance removed from the lower edges thereof so as to provide 5 water-tight inclosures between the shells, said compartments being adapted to receive ballasting material, the inner shell being provided with a well, a series of ramified conduits arranged intermediate of the shells 10 and communicating with said well, a vertically disposed operating shaft arranged in each compartment intermediate of the shells, sluice gates controlling the passage through said conduits and arranged to move vertically in said shafts, intake pipes connected 15 with said conduits, the outer ends of said intake pipes being vertically disposed in a plane beneath that of the upper edges of said shells, a hood arranged about each of 20 the orifices so as to deflect material to the sides thereof and compel the water to flow from a point beneath said orifices and supporting means for each of said hoods arranged to prevent the passage of obstacles 25 into said orifices.

17. A combined crib and intake provided with a centrally disposed well having a series of inlets and communicating with the intake shaft leading to shore, a series of conduits communicating with the inlets of the well, a vertically disposed shaft arranged 30 above each of said conduits and at a point intermediate of the well and the outer wall of the crib, means operable in said shaft 35 whereby passage through said conduits is controlled, a passage encircling the upper part of the well and communicating with each of said vertically disposed shafts, a series of intake pipes communicating with said 40 conduits and provided with upturned outer ends, a deflecting hood arranged about each upturned end of said intake pipes whereby the water is compelled to flow upward into said intake pipes, and means intermediate of the hoods and the crib whereby formation

of anchor ice about said hoods may be controlled.

18. A combined crib and intake, comprising a well provided with a series of inlets adjacent the lower portion thereof, the bottom of the well terminating in the intake shaft leading to shore, the wall surrounding the well being provided with inlet conduits communicating with the inlets of the well, each of said conduits being provided with a 50 gate and screen at a point intermediate of the ends of said conduits and an operating shaft within which said gate and screen of each inlet conduit is located. 55

19. A combined crib and intake, provided with a well having a series of inlets circumferentially arranged about the bottom thereof, the well being provided with upwardly converging sides, the bottom of the well terminating in the intake shaft leading to 60 shore, a series of conduits, arranged within the wall of the crib, communicating with the inlets of the well and provided with ramified ends, an operating shaft arranged in the wall of the crib and about the well, and 65 means located within said shaft whereby the passage through said conduits may be controlled. 70

20. A combined crib and intake, comprising a pair of concentrically arranged shells 75 provided with a bottom at a point removed from the lower edges thereof, said shells being provided with a series of aligned flanged ports adjacent the lower edges thereof, conduits arranged intermediate of the 80 aligned ports of both shells, means located in each of said conduits whereby passage therethrough may be controlled, and means whereby the water beneath the bottom may be extracted when the shells are being set- 85 tled into place.
